US00D536822S

(12) **United States Design Patent** (10) **Patent No.:** **US D536,822 S**
(45) **Date of Patent:** **** Feb. 13, 2007**

(54) **TRACK**

(75) Inventors: **Steven Pyshos**, Peachtree City, GA (US); **Gregg Lehman**, Peachtree City, GA (US)

(73) Assignee: **Cooper Technologies Company**, Houston, TX (US)

(**) Term: **14 Years**

(21) Appl. No.: **29/251,936**

(22) Filed: **Jan. 17, 2006**

Related U.S. Application Data

(63) Continuation of application No. 29/233,364, filed on Jun. 30, 2005.

(51) **LOC (8) Cl.** **26-99**

(52) **U.S. Cl.** **D26/138**

(58) **Field of Classification Search** D26/128-138, D26/113, 115, 118, 120, 122, 141, 142, 152, D26/61, 63, 123, 140; 362/219, 391, 249, 362/147, 404, 223; D25/123, 138; D13/155; D8/354

See application file for complete search history.

Primary Examiner—Freda S. Nunn

Assistant Examiner—Kevin K. Rudzinski

(74) **Attorney, Agent, or Firm**—SAIDMAN DesignLaw Group

(57) **CLAIM**

The ornamental design for a track, as shown and described.

DESCRIPTION

This application is related to co-pending applications: Ser. No. 11/322,837, filed Dec. 30, 2005 and titled “Halo Flex Track”; Ser. No. 11/324,099, filed Dec. 30, 2005 and titled “Halo Power Supplies”; Ser. No. 11/323,231, filed Dec. 30, 2005 and titled “Halo Clam Shell Connections”; and Ser. No. 11/323,755, filed Dec. 30, 2005 and titled “Halo Hubs and Connections”.

FIG. 1 is a top perspective view of a track showing our new design;

FIG. 2 is a left end view thereof, the right end being a mirror image; and,

FIG. 3 is a top plan view thereof, the bottom view being a mirror image.

The jagged lines in FIGS. 1 and 2 indicate indeterminate length. The broken lines form no part of the claimed design.
